UNITED STATES PATENT OFFICE.

FRANCIS M. ROSENFELD, OF NEW YORK, N. Y., ASSIGNOR TO IMPORT SALES COMPANY,
A CORPORATION OF NEW YORK.

POCKET FLASH-LIGHT.

1,150,066.

Specification of Letters Patent.

Patented Aug. 17, 1915.

Application filed March 10, 1915. Serial No. 13,319.

To all whom it may concern:

Be it known that I, FRANCIS M. ROSENFELD, a citizen of the United States, and a resident of the borough of Manhattan, city, county, and State of New York, have invented certain new and useful Improvements in Pocket Flash-Lights, of which the following is a description.

My invention relates to portable electric flash lights and particularly to such devices which are small in size and are adapted to be carried in the pocket in the same manner as are pencils, fountain pens, etc.

The object of my invention is to provide such a device, which will be small and compact and which shall be provided with a circuit making device, which cannot be accidentally operated to close the circuit.

It is also an object of my invention to make use of the circuit closing device as a means for retaining the flash light in the pocket.

In the drawings, Figure 1 is an elevation of my improved device; Fig. 2 is also an elevation taken at right angles to Fig. 1; Fig. 3 is a longitudinal sectional view; and Fig. 4 is a transverse sectional view, taken on the line 4—4 of Fig. 3.

Referring to the drawing, 10 represents the casing which is preferably of metal or some other conducting material. Within this casing is a battery 11 of the type commonly used in devices of this character, having at its ends the terminals 12, 13. This battery is preferably insulated from the casing by a coating of insulating material, such as is shown at 14.

The reflector 15 is removably secured in one end of the casing in any suitable manner, as for instance, by the bayonet joints indicated at 16. The reflector serves also as a socket, into which the base of the lamp 17 may be screwed. When these parts are in the position shown in Fig. 3, the circuit runs from the terminal 12 of the battery through the lamp filament and reflector to the casing and thus the casing may be said to form one terminal of the lamp circuit.

Referring now to the other end of the battery and casing, 18 designates a suitable cap, which may be removably secured to the end of the casing in any desired manner, as for example, as shown at 19. Some suitable means, such as the coiled spring 20 for contact with the terminal 13 of the battery is

secured to the inner side of the cap, but is insulated therefrom by some suitable means, such as the washer 21 of insulating material. Secured to the outside of the cap is the L-shaped spring clip 22, which is insulated from the cap by the washer 23 of insulating material. Some suitable means, such as a rivet 24 is employed for securing both the spring 20 and the clip 22 to the cap 18. This rivet serves to electrically connect the clip and spring and it should be insulated from the cap 18 by some suitable means, as shown at 25.

From the above, it is apparent that the casing 10 is connected through the lamp to the terminal 12 of the battery, thus forming one terminal of the electric lamp circuit and that the spring clip 22 is connected through the spring 20 to the other terminal of the battery and thus forms the other terminal of the electric lamp circuit. Therefore when an electrical contact between the casing 10 and the clip 22 occurs, the circuit through the lamp will be completed.

The spring clip 22 not only serves as a circuit closing device, but also as a means for retaining the flash light in the pocket. For this reason it is preferable, though not necessary, that this clip should be normally spring pressed into physical contact with the casing or with some projection on the casing. In the device shown herein, I provide the free end of the spring clip with an insulator 26 which is normally in physical contact with the casing, but which prevents electrical contact between the clip and casing. When it is desired to close the lamp circuit, it is merely necessary to apply force with the thumb at an intermediate point in the spring clip to cause contact between such point and the casing.

While I have herein shown an insulator applied to the clip, to insulate it from the cap, this result may be accomplished in numerous other ways, as will be readily understood.

The operating of my improved device should be apparent from the foregoing.

It is obvious that the spring clip, which is normally pressed toward the casing, will effectively retain the device in the pocket.

It is also clear that in the preferred form of my invention the lamp circuit cannot be accidentally closed, either when the lamp is in the pocket or when it is removed there.

from, since it requires a certain degree of force to effect contact between the intermediate portion of the clip and the casing.

While I have disclosed one particular embodiment of my invention, I do not wish to limit myself to this embodiment, which is shown merely as an example of the many forms which my invention may take. Obviously many changes may be made by those skilled in the art, without departing from the spirit of my invention.

What I claim is:

1. In a device of the character described provided with an electric circuit, including a battery and lamp, a combination of a casing, of conducting material forming one terminal of the circuit and a spring clip adapted to retain the device in the pocket and forming the other terminal of the circuit, one end of said clip being supported by, but insulated from, the casing and the other end thereof being normally in physical contact with, but insulated from, the casing, said clip being adapted to be manually forced at a point intermediate its ends into electrical contact with the casing to complete the circuit.

2. In a device of the character described, provided with an electric circuit, including a battery and a lamp, the combination of a casing of conducting material forming one terminal of the circuit and a spring clip adapted to retain the device in the pocket and forming the other terminal of the circuit, said clip being normally in physical contact with, but insulated from the casing, and adapted to be manually forced into electrical contact therewith to complete the circuit.

3. In a device of the character described, provided with an electric circuit, including a battery and a lamp, the combination of a casing of conducting material forming one terminal of the circuit and an L-shaped spring clip forming the other terminal of the circuit, one end of said clip being connected to, but insulated from the casing, and the other end thereof being normally spring pressed against the casing and pro-

vided with an insulator to insulate itself therefrom, said clip being so constructed that its intermediate portion may be manually forced into contact with the casing to complete the circuit.

4. In a device of the character described, a casing of conducting material, a battery within said casing, and provided with a terminal at either end thereof, a lamp mounted in one end of the casing and electrically connected to one terminal of the battery and to the casing, a cap mounted at the other end of the casing and a spring clip one end of which is secured to and insulated from said cap and electrically connected to the other terminal of the battery, the other end of said clip being normally in physical contact with, but insulated from the casing, said clip being adapted to be manually forced at a point intermediate its ends into electrical contact with the casing, to complete the circuit through the lamp.

5. In a device of the character described, a casing of conducting material, a battery within said casing, and provided with a terminal at either end thereof, a lamp mounted in one end of the casing and electrically connected to one terminal of the battery and to the casing, a cap mounted at the other end of the casing, and a spring clip one end of which is secured to and insulated from said cap, a coiled spring also secured to and insulated from said cap and electrically connecting the clip with the other terminal of the battery, the other end of said clip being normally in physical contact with, but insulated from the casing, said clip being adapted to be manually forced at a point intermediate its ends into electrical contact with the casing to complete the circuit through the lamp.

In testimony whereof I have signed this specification in the presence of two subscribing witnesses.

FRANCIS M. ROSENFELD.
